MELTING AND HOLDING FURNACE

John G. G. Frost, Cleveland, Ohio, assignor to
 The National Smelting Company, Cleveland,
 Ohio, a corporation of Ohio

Application May 18, 1931, Serial No. 538,144

1 Claim. (Cl. 266—33)

This invention relates to the art of casting metals, and particularly to improvements in melting and holding furnaces for use in connection with the melting of aluminum and alloys, and 5 other alloys containing small percentages of aluminum, nickel, tin, or other non-ferrous metals, in which a low iron content is desired. In the casting of metals of this character it is usually the practice to melt the metal in a large 10 furnace and to either cast into ingots and remelt in an iron pot or transfer the molten metal from the large furnace directly to the iron pot for finishing. This practice is usually carried out in all types of casting, whether it be sand 15 casting, permanent mold casting, or die casting.

In each case it is the practice to provide a melting pot that is suitably heated externally by gas, oil or electricity near the casting operation. In the die casting of such metals, the iron melting 20 pot is positioned adjacent the casting machine so that the gooseneck ladle that is generally used can be conveniently operated between the molten metal and the casting machine. This arrangement, and the open pot usually employed in connection with sand and permanent mold casting, 25 makes it practically impossible to use anything other than an externally heated melting and holding pot of iron.

There are many disadvantages that are inherent with the use of the iron pot. In ordinary practice, iron pots are very short lived, even when particular attention is paid to the various linings that are frequently used and, as a result, considerable money is expended in replacing worn out iron pots, and time is wasted in coating such holding pots. Many alloys, and silicon alloys in particular, have a great tendency to dissolve iron from the conventional melting and holding pot of iron, and heretofore it has 30 been very difficult to control the iron content of such alloys because of this disadvantage.

The greatest disadvantage in using the conventional iron melting and holding pot is the tendency of the molten metal to pick up or dissolve iron from the pot and thus increase its iron content. In the casting of non-ferrous metal alloys, it is very essential that the iron content be maintained at a low percentage, since a high percentage iron may have a deleterious effect, 45 such as cracking, on the castings being produced. This is particularly true in die casting, where thin-sectioned, intricate castings are made of aluminum and alloys thereof.

It is one of the objects of the present invention to provide a melting and holding furnace of

improved construction which may be conveniently located at the place of casting the metal, and which will overcome the many disadvantages that are inherent with the use of the so-called melting and holding pots of iron.

Another object is to provide a melting and holding furnace for the casting of aluminum, aluminum alloys, and other alloys containing small percentages of aluminum, nickel, tin or other non-ferrous metals which tend to pick up 5 iron when melted, of such construction that considerable time and expense can be saved as compared with the use of conventional holding pots, and which will tend toward a more economic production of satisfactory castings.

Another object is to provide a melting and holding furnace of such construction that the molten metal available for use in the casting operation will be maintained at the proper temperature for casting, and will be free of skimmings or 10 dross.

A further object is to provide a melting and holding furnace for use in connection with the casting of aluminum, aluminum alloys, and other alloys of the character referred to, which 15 may be used adjacent and in connection with a die casting machine, and in which the molten metal available for use is contained within a chamber of refractory material whereby to avoid an increase in the iron content of the molten 20 metal.

A further object is to provide a melting and holding furnace for use in the casting of metals in which the surface of the molten metal available for use is separated from the surface of 25 the molten metal that is being subjected to the melting heat, in order that the body of metal available for use will be free of skimmings and other surface impurities, but subjected to the 30 heat of the metal being melted.

With the above and other objects in view which will be apparent from the following detailed description, the present invention consists in certain features of construction or combinations of parts which will be readily apparent to those skilled in 35 the art to which the invention appertains.

In the drawings which illustrate a suitable embodiment of the invention,

Figure 1 is a side elevation of a melting and holding furnace, portions of the same being 40 broken away and shown in section and shown in cooperative relation with one type of die casting machine;

Fig. 2 is a fragmentary view similar to Fig. 1 showing the gooseneck ladle of the die casting 45

machine in its lowered filling position within the molten metal supply chamber;

Fig. 3 is a transverse section taken substantially on the line 3—3 of Fig. 1;

5 Fig. 4 is a vertical section taken substantially on the line 4—4 of Fig. 1, showing the position of the charging opening for the furnace; and

10 Fig. 5 is a section taken substantially on the line 5—5 of Fig. 3 showing the position of the flue for the furnace.

Referring specifically to the accompanying drawings in which like numerals refer to like parts throughout the several views, the melting and holding furnace of the present invention is 15 arranged to replace the conventional iron holding pot that has heretofore been used in the casting of non-ferrous metal alloys. The furnace proper, as shown in the various views, preferably comprises a rectangular shaped shell 1 supported by 20 suitable base members 2. The bottom of the shell 1 is preferably covered with a relatively thick layer 3 of sand or other suitable material, and the layer of sand is surrounded with a liner 4 which may be of common fire brick.

25 A layer of suitable insulation 5 is arranged over the bottom liner 4 and this layer of insulation is in turn completely covered with a relatively thick refractory material 6. The sides and ends of the shell adjacent and above the material are 30 also provided with relatively thick refractory material 7.

The space within the sides and ends of the refractory material, as shown in Figs. 1 and 4, is 35 divided into two chambers A and B by a fire wall 8 of refractory material which extends between the sides of the apparatus. This fire wall 8 does not completely separate the chambers A and B, but extends downwardly in such a manner that its lower edge will always lie below the level 9 40 of molten metal contained therein to permit a flow of the molten metal between the two chambers and to prevent the accumulation of skimmings and dross on the molten metal that is available for use.

45 The chamber A, as will be later described and as shown in the drawings, is open at its top and contains the molten metal that is available for immediate use. This chamber in reality forms the holding pot for available molten metal.

50 The chamber B, defined by the transversely extending fire wall and the one end and the sides of the device, is completely enclosed to form the furnace proper. The enclosure for the chamber B preferably embodies a rectangular shell portion 55 including sides 10 and ends 11 suitably lined with refractory material 12, and a roof portion 13 which is also of refractory material 14.

One end 11 of the enclosed heating portion of the furnace is provided with one or more suitable 60 openings 15, which, in conjunction with suitable burners 16, are arranged to project a heating flame substantially horizontally above the surface of the metal in the enclosed heating chamber. As shown in Fig. 4, the lining 14 of the roof 65 is arched in order to radiate the heat downwardly onto the metal in the chamber B.

The products of combustion are discharged 70 from the enclosed chamber B through a suitable flue 17 arranged in the wall containing the heater openings 15, but at a point remote from the heater openings 15. The flue 17 opens into the closed chamber near the normal level of the metal.

One side 10 of the enclosure is formed with 75 a relatively large charging opening 18 which is

arranged to be closed by a suitable refractory lined door 19. The furnace is provided with a tap hole opening 20 disposed adjacent the bottom and extending through one of the sides.

In the use of the melting and holding furnace 5 of the present invention, the transversely extending fire wall 8 separates the molten metal that is available for immediate use from the metal that is being melted within the chamber B, but does not retard the motion of the molten metal from 10 the chamber B into the chamber A.

The primary function, however, of the transversely extending fire wall 8 is to separate the surfaces of the molten material in the chambers A and B so that the skimmings and dross will rise 15 to the surface within the chamber B and will be prevented from floating to the available metal in the chamber A. It will be readily apparent that the metal that is available for use in the chamber A will be free of skimmings or dross.

20 One of the advantageous features of the furnace construction is that the skimmings and other objectionable material remain in the furnace proper and can be easily removed without contaminating the metal in the holding chamber 25 A. Furthermore, the motion of the molten metal in the chamber B underneath the fire wall 8 and into the chamber A, serves to keep the molten metal in the chamber A at the proper temperature for casting.

30 Another advantageous feature of the furnace construction described is that larger ingots can be melted than is possible in the conventional melting and holding pots, thus reducing the initial cost of the metal and saving considerable 35 time in charging the furnace. Furthermore, ingots having a higher content of iron may be used for charging, since there will be no chance of iron pick-up, which occurs when conventional 40 iron holding pots are used. This thus tends toward the economic production of castings having the desired minimum iron content.

45 A further advantage derived from the use of a melting and holding furnace of the character just described is that suitable and desirable fluxes may be used during the melting and holding of the molten metal. Heretofore this has not been possible when conventional holding pots formed of iron, graphite crucibles or the like were used, since the flux when used in connection with alloys would attack the iron pot or crucible and greatly increase the iron content of the metal being melted and held by these containers.

50 In order to show the advantageous features of the furnace of the present invention, the same is 55 shown in cooperative relation with one type of die casting machine that is frequently used. In this machine a pair of mold members 21 and 22 are used and the mold member 22 is rigidly secured to a vertically extending member 23 and the mold 60 member 21 is mounted on a reciprocating head 24 that is slidably mounted on a pair of spaced guide rods 25.

The rods 25 at one end are secured to the vertically extending member 23 and at the other end 65 to a support 26. The support 26 carries a rotatable shaft 27 having a crank arm 28 at one end thereof. This crank arm is connected by means of a pitman rod 29 to the reciprocating head 24. This device is arranged adjacent the open holding chamber A of the furnace, as shown in Fig. 1, 70 and the vertically extending member 23 is provided with a sprue opening 30 which is positioned slightly above the end 7 of the open chamber A. 75

The molten metal is forced under pressure by compressed air into the sprue opening 30 by means of a gooseneck ladle 31 that is arranged directly over the open chamber A. This ladle 31 is formed with an upward extension 32 and is supported by upper and lower pairs of links 33 and 34, respectively. The lower links 34 are pivoted to the ends of crank arms 35 that are rigidly secured to a shaft 36 which is rotatably mounted within a bracket 37 secured to the upwardly extending member 23. The upper links 33 likewise are pivoted to the member 32 and are rigidly secured at their other ends to a shaft 38 that is also mounted in the bracket 37. The shaft 38 is provided with a gear segment 39 which is in mesh with a reciprocable rack 40 and the shaft 36 is provided with a gear segment 41 which is also in mesh with a reciprocable rack 42. When the racks 40 and 42 are reciprocated, the ladle, through the connecting mechanism, is moved into and out of the metal in the chamber A. In its lowermost position, as shown in Fig. 2, the gooseneck ladle 31 is filled with the molten metal in the supply chamber A, and upon reciprocation of the racks 40 and 42 the ladle 31 is moved upwardly to the position shown in Fig. 1, in which position the open end of the ladle is brought into engagement with the upwardly extending member 32 with its opening in alignment with the sprue opening 30. Pressure is then exerted within the ladle through a compressed air conduit 43 that is in communication with the interior of the ladle, which forces the molten metal within the ladle through the sprue opening 30 and into the chamber 44 formed by the mold members 21 and 22. The pressure within the ladle 31 is maintained until the metal within the mold chamber 44 has set, and then the pressure within the ladle is released and the ladle moved again to its lowermost position within the supply chamber A below the surface of the molten metal, where it is again filled with the molten metal and ready for the casting of the next article that is to be formed in the die casting machine.

The advantages of the furnace of the present invention can be readily appreciated when the melting and holding furnace is used in connection with a die casting machine such as the type shown in the drawings. This arrangement provides a source of clean molten metal that is maintained at the proper temperature for casting.

When the furnace construction is used in connection with permanent mold or sand casting, the molten metal may be removed by a ladle of any conventional construction, and the supply of molten metal will always be clean and be at the right temperature, thus eliminating the disad-

vantages that are inherent with the conventional iron holding pots that have been used heretofore.

It is obvious from the drawings and foregoing description that the present invention provides means whereby non-ferrous metals such as aluminum and alloys thereof, may be economically cast without danger of increase in the iron content thereof from the holding pot or furnace, thus tending toward the efficient production of satisfactory castings.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claim.

What I claim is:

A furnace for melting and holding non-ferrous metals in which a low iron content is desired, comprising a refractory lined bottom, end, and side walls, one of said end walls and a portion of each of the side walls extending a substantial distance above the remaining end wall, a cover of refractory material extending over that portion of the furnace defined by the upwardly extending wall portions, and a wall formed of refractory material extending downwardly from the free end of said cover to a point below the normal operating level of the molten metal in the furnace, thereby dividing the furnace into a closed heating portion and an open holding portion, said refractory wall being spaced from the bottom of the furnace to permit molten metal to flow freely from the heating portion into the open portion, means for projecting a flame substantially horizontally through one of the walls of the closed heating portion of the furnace into the interior of said heating portion above the metal, a charging opening in said closed heating portion, a door for closing said opening, and a flue passageway opening into said closed heating portion for carrying off the products of combustion, said flue passageway being positioned in the same wall of the closed heating portion as the means for projecting a flame, and having its opening into said closed heating portion adjacent the normal level of the molten metal, for carrying off the products of combustion, said flue opening being also positioned with respect to said flame projecting means, so that the hot gases projected substantially horizontally across the closed heating portion and above the metal will return substantially horizontally over the metal to escape through the flue opening.

JOHN G. G. FROST.
